DESIGN FOR A CLOCK

Nathan George Horwitt, New York, N. Y.

Application December 3, 1934, Serial No. 54,228

Term of patent 7 years

To all whom it may concern:

Be it known that I, Nathan George Horwitt, a citizen of the United States, residing in the city of New York, in the county of Queens and State of New York, have invented a new, original and ornamental Design for a Clock, of which the following is a specification, reference being had to the accompanying drawing, forming a part thereof.

Figure 1 is a perspective view of a clock, showing my new design.

Fig. 2 is a front elevation of the clock shown in Fig. 1, the numerals in both instances being merely representative.

The novelty of the design resides in the bull's-eye or iris of an eye appearance of the portion within the inner circle, said circle representing a line of demarcation between different surface appearances. Also there is novelty in the beauty spot effect of the "seconds" dot, that is the small circular area shown with the number 30.

I claim:

The ornamental design for a clock, as shown and described.

NATHAN GEORGE HORWITT.
